6321X

A. Gorham,
Stump Elevator.
Patented Jan. 7, 1831.

The schedule referred to, in these Letters —
Patent and making part of the same containing
description in the ~~like~~ words of the said Abijah
Gorham himself of his improvement in the machine
called "Gorham's Stump Machine"

This improvement in taking out stumps by this
machine is calculated to be of great utility, it performs
the work in an expeditious manner, and so that three
yoke of Oxen and three men, can easily raise and clear
out forty stumps in one day, of its operation, from land
of ordinary quality; and by a recurrence to the annexed
Draft of the machine, it may be observed that one
yoke of Oxen, appended to the pole, marked A, is suf-
ficient to move the machine to any part of the field
required, and two yoke of Oxen attached to the chain
or rope, marked B, is sufficient to raise stumps of
middling size, and from thence to four yoke of Oxen
can raise stumps of the largest size; and for other
particulars with regard to said machine, reference is
made to the annexed drawing.

In testimony that the above is a true specification
of my said invention and improvement, as above described
I have hereto set my hand and seal this third day of
Jane, in the year of our Lord one thousand eight
hundred and thirty

Abijah Gorham
